UNITED STATES PATENT OFFICE.

WILLIAM R. MUNZER, OF EMETTA, MINNESOTA.

AX.

1,378,973.

Specification of Letters Patent. Patented May 24, 1921.

Application filed December 20, 1920. Serial No. 431,971.

To all whom it may concern:

Be it known that I, WILLIAM R. MUNZER, a subject of Germany, residing at Emetta, in the county of St. Louis and State of Minnesota, have invented certain new and useful Improvements in Axes, of which the following is a specification, reference being had therein to the accompanying drawing.

This invention relates to certain improvements in axes and has special reference to a lumberman's ax for use in getting out pulp wood, ties and the like and is an improvement over my Patent No. 1,330,213 of Feb. 10, 1920, the principal object being to provide a more practical and useful instrument than heretofore known.

Another object of this improvement is to provide means whereby the handle of the ax after becoming badly worn is prevented from slipping forwardly longitudinally through the ax head.

Still another object is to provide a form of such ax exceptionally easy of construction.

Other objects and advantages will appear in the further description of the invention.

Referring to the accompanying drawings forming part of this application and in which like reference characters indicate like parts:

Figure 1 is a side elevation of one of the improved axes,

Fig. 2 is a central transverse sectional view through the ax longitudinally of the handle and showing the same in active position upon a log;

Fig. 3 is an enlarged broken elevation of two diagonally opposite halves of the edges of the ax, and

Fig. 4 is an enlarged elevation of the opposite side of the ax to that shown in Fig. 1.

The head of the ax is substantially the form of a common double bitted ax having two arcuately shaped cutting bits 2-2 and with the handle socket 3 formed substantially centrally thereof as is common, and a third cutting or peeling bit 4 is formed upon the forward edge of the head intermediate of the cutting bits 2-2. However this third bit, instead of being arcuate in form is straight for the major portion of its length, the cutting edge being parallel with the central line of the bits 2-2.

The bit 4 has not only a straight cutting edge but has a flat external lower surface disposed at an angle to the adjacent back

wall 6 of the head of the ax; thus bringing the cutting edge of the bit 4 slightly above a plane with the inner wall of the socket 3 next thereto.

Just slightly forward and above the angle 7, formed by the intersection of the surfaces 5 and 6, is formed the shoulder 8 longitudinally of the base of the bit 4 and which shoulder forms an end wall to the socket 3 in the head of the ax against which the handle 9 abuts when properly assembled within the ax head. This abrupt stop for the end of the handle 9 is essential in preventing the latter from being forced through the head of the ax when becoming loose therein as the ax is being employed as a scoop for scooping off the smaller limbs of a tree as shown in Fig. 2.

A still further novel feature of my present improvement is that the upper face of the bit 4 and the upper edge of the ax head adjacent thereto are of the same continuous arcuate plane to both simplify the construction of the ax and the sharpening process thereof, that portion of the end of the handle 9 projecting above the edge of the shoulder 8 being also coincidentally shaped as well as the holding wedge 10 which is driven into the end of the handle just above the shoulder 8. The convenience in removing the wedge 10 is seen in that when such is desired that portion of the handle above the wedge and protruding beyond the edge of the socket may be cut off with a chisel and the wedge thus made readily accessible for extraction.

In the removing of branches from tree trunks such as are harvested for pulp wood the ax is used as a scoop with the blade 4 engaging the smaller branches as shown in Fig. 2, while, when a larger branch, as shown at 12, is to be removed, the ax is turned and either of the bits 2 is used as a common chopping ax. When the ax is used for scooping off the branches or for removing bark as is customary in getting out ties, etc., it is very essential that the double bulbed handle as shown in Fig. 1 be used, as it otherwise becomes very hard to grip the ax sufficiently for such purpose.

Having thus described my invention what I claim and desire to secure by Letters Patent, is:

1. The combination with a double bitted ax of the character described having the usual handle socket therein, of a third scoop-

like bit extending forwardly of the front edge of the ax and formed integral therewith, said third bit being disposed at an angle to the axial line of the handle socket, 5 having a straight cutting edge, a straight flat under bearing surface, and a shoulder at the base of the third bit terminating the handle socket, substantially as described.

2. The combination with a double bitted 10 ax of the character described having the usual handle socket therein, of a third scoop-like bit extending forwardly of the front edge of the ax and formed integral therewith, said third bit socket, having a straight 15 flat under bearing surface disposed at an angle to the axial line of the handle, and a shoulder longitudinally of said third bit ter-

minating the lower portion of the handle socket, substantially as described.

3. The combination with a double bitted 20 ax of the character described having the usual handle socket therein, of a third scoop-like bit extending forwardly of the front edge of the ax and formed integral therewith, and a shoulder at the base of said third 25 bit extending longitudinally thereof and forming an abrupt termination of a portion of the handle socket.

In testimony whereof I hereunto affix my signature in the presence of two witnesses. 30

WILLIAM R. MUNZER.
